UNITED STATES PATENT OFFICE.

JAMES A. ROBERTS, OF MARIETTA, OHIO.

PIPE-WRENCH.

1,185,346.

Specification of Letters Patent.

Patented May 30, 1916.

Application filed December 29, 1915. Serial No. 69,160.

To all whom it may concern:

Be it known that I, JAMES A. ROBERTS, a citizen of the United States, and a resident of Marietta, in the county of Washington, ton and State of Ohio, have invented certain new and useful Improvements in Pipe-Wrenches, of which the following is a specification.

My invention relates to pipe wrenches, and some of the objects thereof are to provide such a device which is easily adjusted to and removed from the pipe, which takes a firm grip and will not slip, and which is strongly made and durable in service.

A further object is to provide a replaceable die which serves as the biting jaw and which die provides eight edges all of which can be worn out before a new die is required, and, with these and other objects, my invention consists in the structure hereinafter described and claimed.

My invention is fully described in the following specification, of which the accompanying drawings form a part, in which like characters refer to like parts in each of the views, and in which:—

Figure 1 is a side view of my wrench in a position preparatory to engagement with a pipe; Fig. 2 is a bottom plan view of Fig. 3; Fig. 3 is a view similar to Fig. 1 with the parts in pipe engaging positions, and partly in section; Fig. 4 is a section taken on the line 4—4 of Fig. 1; and Fig. 5 is a detached view of the die.

The wrench comprises a hook 6 the curvature of which approximates that of the size of pipe for which the wrench is made, as the wrenches will be made of different sizes to meet different conditions, and the straight portion of the hook member is slotted, as shown at 7, and has a pivot pin 8 passed from one leg to the other near the end of the slotted portion of the member 6. Slidably mounted between the legs formed by the slot 7 is a carrier for the die 9, said carrier comprising a body portion 10, a seat 11 for the die 9, a hook 12, and a T-back 13 bearing against the back of the member 6. Carried by the pivot pin 8 is a handle 14 provided with a projection 15 within the member 6 adapted for engagement with the hook 12 of the die carrier when the parts are in inoperative positions, thus locking the

carrier and handle together against upward movement of either and downward movement of the carrier.

When the hook member 6 is engaged with a pipe 16 and the handle 14 is moved out of the perpendicular relationship shown in Fig. 1 to the obtuse angularity shown in Fig. 3 the carrier is forced toward the pipe and the die 9 forced into biting engagement with the pipe, a powerful grip being assured because of the handle leverage and of the sharp edge of the die and, when one of the edges becomes dulled, all that is necessary is to loosen the screw 17 and present a new edge of the die to the pipe 16.

The die 9 will preferably be made square although, obviously, I do not limit myself to such formation, the square form being preferably for the reason that eight edges of the same length are provided.

My wrench is in no respect an adjustable one inasmuch as the pivot 8 is fixed with respect to the hook member 6, although there is naturally a degree of play to the carrier which will adapt the wrench to pipes of varying diameters. There is actually but one jaw, the die 9, inasmuch as the hook 6 encircles the pipe and approximately conforms thereto without any biting effect, and a strong and powerful wrench is thus provided.

Having fully described my invention, what I claim as new, and desire to secure by Letters Patent, is:—

A pipe wrench, comprising a jaw member hook-shaped at its outer end and provided with a slot in the body portion thereof, a die carrier slidable in said slot and of T-shape in cross section with the web thereof resting in said slot and with the cross-bar bearing against the back of said jaw member, a die detachably held on the edge of said web portion and serving to imprison said carrier in said slot, and an operating lever pivoted in said slot and bearing against the under side of said carrier.

In testimony whereof I have signed my name to this specification in the presence of two subscribing witnesses.

JAMES A. ROBERTS.
